UNITED STATES PATENT OFFICE.

ORLANDO L. STARKEY AND ELISHA W. POSTON, OF FORT WAYNE, INDIANA,
ASSIGNORS TO ORLANDO L. STARKEY, OF SAME PLACE.

IMPROVEMENT IN PAPER-TRIMMING MACHINES.

Specification forming part of Letters Patent No. 118,066, dated August 15, 1871.

To all whom it may concern:

Be it known that we, ORLANDO L. STARKEY and ELISHA W. POSTON, of Fort Wayne, in the county of Allen and State of Indiana, have invented certain new and useful Improvements in Wall-Paper Butting-Machines; and we do hereby declare that the following is a full, clear, and exact description thereof, which will enable others skilled in the art to make and use the same, reference being had to the accompanying drawing forming part of this specification, in which—

Figure 1 is a front elevation, partly in section. Fig. 2 is a top view, and Fig. 3 a vertical transverse section of our improved wall-paper butting-machine. Fig. 4 is a detached view of one end of cylinder B.

Similar letters of reference indicate corresponding parts.

The nature of our invention consists in the arrangement and construction of an apparatus to be used for “butting” both edges of wall-paper at the same time, by the simultaneous action of two sets of rotating cutters, whose edges pass each other in such a manner as to cut like shears, said cutters being arranged on rotating cylinders, between which the paper to be operated is fed. One set of cutters is stationary, while the other is made adjustable, so as to meet the requirements of different widths of paper. Our invention relates particularly to the arrangement and adjustment of the cutters, both in relation to the desired width of paper, and also to the device by which the cutting-edges of the adjustable cutters are held in continual contact, as will be more fully described.

To enable others skilled in the arts to make and use our invention, we will now proceed to describe its construction and operation.

A represents a cylinder, which is secured in suitable bearings on a convenient frame. This cylinder is composed of two sections, *a* and *b*. Section *a* is fixed permanently to the axle, and revolves with it. This section is provided with a cutting flange or disk, *c*, which is secured to said cylinder near its outer end, as seen in Fig. 1. Section *b* of cylinder A is fitted on the axle so as to be adjustable longitudinally to any desired width while it revolves with the axle. The adjustable section of cylinder A is also provided with a cutter, *d*, in every respect similar to cutter *c*. The surface of this cylinder is covered

with flock, so as to present a slightly-yielding surface, which enables the cylinder to take a firm hold on the paper without in the least injuring it. The outer end of section *b* is provided with a metallic flange, *e*, as seen in Fig. 1. B represents a cylinder, which is placed directly over cylinder A, where it is secured in suitable bearings *ff*. These bearings are adjustable vertically, and are held in position by means of spiral springs, as seen in Fig. 1, so as to allow said cylinder B to accommodate itself to any thickness of paper or any irregularities therein. The general arrangement of the cylinder B is, so far as the sections thereof and the cutters thereon are concerned, exactly identical with the lower cylinder A. It being divided in sections *a'* and *b'*, it is also provided with cutting-disks *c* and *d*. These disks are made somewhat concave, and are so placed as to bring their concave sides facing each other, thus presenting a shear-like surface to the paper. The outer end of section *b'* is provided with an adjustable metallic thimble or sleeve, which fits over the outer end of the section, as seen in the drawing; around this thimble there is a groove, *g*, into which flange *e* fits snugly, for the purpose of holding the sections in their relative positions at any point of adjustment. A spiral spring, *l*, is inserted in or applied to a suitable seat in the end of section *b'* of cylinder B, as seen in Fig. 4, and serves to force said cylinder longitudinally so as to press the edges of the cutting-disks together. *i* represents a nut, through which a screw, *j*, passes. The said nut is, on its lower side, provided with a lip, *h*, which extends downward and enters the groove *g*. When the screw *j* is rotated the nut *i* is traversed over said screw, and carries with it the section *b'* of cylinder B. The movement of said section also carries section *b* of cylinder A in the same direction, the two sections always maintaining the same relative position. Thus the cutters on the sections *b* *b'* of the cylinders may be, at will, so adjusted in relation to their distance from the cutters *c* *c'* on the not-adjustable parts of the cylinders as to be adapted to cut any desired width of paper. At the outer end of the cylinder A a spiral spring, *k*, is or may be inserted in a suitable seat formed in the end of the cylinder over the axle, which presses against the side of the frame for the purpose of meeting and resisting the pressure of the spring

in the opposite end of section *b'* of cylinder B. These two springs act in combination for the purpose of constantly engaging the cutting-edges of the disks while operating, as before described. D represents a reel, which receives the paper which has passed through the machine, and is operated by means of a set of suitable pulleys and belt. E represents a receiving-roller, which assists in delivering the paper from the cutters to reel D. F represents a guide fixed to or made adjustable on a table, H, so that it greatly facilitates feeding the paper to the cutters and keeping it in line with them. G represents the guide, which is adjusted laterally by means of a screw, *n*, which passes through a suitable nut secured to the under side of the guide, which is held in position by it. This guide G has on its inner side a spring, *o*, against which the end of the roll of paper to be operated upon is pressed by the hand of the operator. When the guide is placed in the proper position the roll of paper through which the rod *m* is passed is placed in position

and is forced by the hand against the spring, and the end of the paper is inserted between the rollers or cylinders, the cutters of which are adjusted to the desired width, and the apparatus is put in operation. If the paper is found to deviate from the desired line, it is pressed with more force against the spring, or it is relieved so as to shift it to the desired line of travel without stopping the machine.

Having thus described our invention, we claim as new and desire to secure by Letters Patent—

The cylinders A and B, provided with cutters *c c'* and *d d'*, flange *e*, and groove *g*, spiral springs *l* and *k*, nut and screw adjustment *i* and *j*, all combined and operating in the manner and for the purposes substantially as described.
